Thomas S. Fox.

UNITED STATES PATENT OFFICE.

JOSEPH F. GREVER, OF NEW YORK, AND THOMAS S. FOX, OF BROOKLYN, NEW YORK.

FILM-HOLDING DEVICE.

1,398,458.

Specification of Letters Patent. Patented Nov. 29, 1921.

Application filed November 22, 1920. Serial No. 425,932.

To all whom it may concern:

Be it known that we, JOSEPH F. GREVER and THOMAS S. Fox, citizens of the United States, residing at New York city, county of New York, and Brooklyn, in the county of Kings and State of New York, have invented certain new and useful Improvements in Film-Holding Devices, of which the following is a specification, reference being had 10 therein to the accompanying drawing.

Our invention relates to improvements in holding devices, and more particularly has reference to a holding device for printing films. In devices of this character small accurate adjustment at right angles are required and constant use of the device develops wear in the bearings which render accuracy very difficult. One of the objects of this invention is to overcome this difficulty 20 while at the same time preserving a simple, light, and accurate form of device which can be conveniently manipulated and carried around.

In the accompanying drawing, we have 25 illustrated in Figure 1 in perspective, parts being broken away, a suitable form of film frame holder of the character described. Fig. 2 is a plan view looking down upon the device shown in Fig. 1 in inverted position.

30 3 indicates a suitable holding or retaining bar for mounting the device upon a board or table and this bar is suitably secured to the guide or bearing 4 by any suitable means. At the opposite end of the 35 bearing 4 is also secured a yoke extension 6 by any suitable means such as the screws 7. 8 indicates a slide block of tapered form as shown, to the back of which is secured the bar 9 by any suitable means such as the 40 screws 5. 10 indicates a filler secured through the wall of the bearing 4 by screws such as 11 so that as the bearing 8 wears, the 45 filler block 10 may be adjusted against the worn surface thereof by turning down on the screws 11. 12 indicates an extension from the bearing 4 against which the spring 13 is compressed between the same and the block 8 when the knurled thumb screw 14 provided with a protractor 15 is rotated, 50 thus permitting of accurate predetermined longitudinal movement of the block 8

and its bar 9 which may be measured by the pointer 16 upon said protractor 15. 17-18 are the usual pintles, the former of which is resiliently projected by the 55 coiled spring 19 under compression, and the latter of which may be projected by the knurled nut 20 with protractor 21 which may be read from the pointer 22. 23 indicates a shoulder or projection from the housing or bearing 4 in the path of the longitudinal movement of the bar 9 serving as a stop therefor.

From the foregoing it will be readily observed that any longitudinal or lateral movement of the bar 9 and its suspended frame may be imparted by the nuts 14 or 20 and any wear giving rise to lost motion between the slide member 8 and block 10 may be taken up by the screws 11, thus providing a 70 simple, light, and easily manipulated device of the character described in which practically all lost motion is avoided.

Of course it will be understood that various modifications may be made in the construction and arrangement of parts without departing from the spirit of the invention as claimed.

We claim:

1. In a device of the character described, 80 a bearing housing, and means in combination therewith for securing the same upon a support, a slide bearing therein, and means for taking up the wear thereof, a transverse bar secured upon said slide bearing, a screw for shifting said slide bearing longitudinally and a resilient member for opposing the action of said screw.

2. In a device of the character described, a bearing housing, and means in combination 90 therewith for securing the same upon a support, a slide bearing therein, and means for taking up the wear thereof, a transverse bar secured upon said slide bearing, a screw for shifting said slide bearing longitudinally and a resilient member for opposing the action of said screw, a projection from said housing for limiting the movement of said bar.

3. In a device of the class described, a 100 tapered channel housing and a bearing longitudinally adjustable therein, means in

combination with said bearing for taking up the wear thereof, resilient backing for said bearing, and means for shifting the same a predetermined distance, frame carrying means upon said bearing, and means upon said housing for limiting the movement thereof and in combination with said

frame carrying means, means for shifting a frame therein a predetermined distance.

In testimony whereof we hereunto affix our signature.

JOSEPH F. GREVER.
THOMAS S. FOX.
